UNITED STATES PATENT OFFICE.

JOSIAH J. DEAL, OF CANTON, OHIO.

COMBINATION-LOCK.

No. 820,557.

Specification of Letters Patent.

Patented May 15, 1906.

Application filed August 12, 1905. Serial No. 273,993.

To all whom it may concern:

Be it known that I, JOSIAH J. DEAL, a citizen of the United States, residing at Canton, Stark county, Ohio, have invented certain 5 new and useful Improvements in Combination-Locks; and I do hereby declare that the following is a full, clear, and exact description of the same, reference being had to the annexed drawings, making a part of this specification, and to the figures of reference marked thereon, in which—

Figure 1 is a perspective view showing a portion of the door and the lock connected thereto for use. Fig. 2 is a view showing the 15 lock-casing and all the different parts properly assembled, illustrating a transverse section of the inner knob-spindle. Fig. 3 is a similar view, except the resetting-disk is removed. Fig. 4 is a view showing the first 20 combination-disk removed and illustrating the position of one of the notched or counting disks. Fig. 5 is a view showing the first notched or counting disk removed and illustrating the partition-plate. Fig. 6 is a vertical 25 section of the lock, showing the same properly connected to a door. Fig. 7 is a detached view of one of the counting-disk-operating bars and springs. Fig. 8 is a detached view of the friction-spring. Fig. 9 is a 30 detached view of the setting disk and pin.

The present invention has relation to combination-locks; and it consists in the different parts and combination of parts herein-after described, and particularly pointed out 35 in the claims.

Similar numerals of reference indicate corresponding parts in all the figures of the drawings.

In the accompanying drawings, 1 represents the lock-case, which is secured to the door 2, as hereinafter described. To an inner knob-spindle 3 is attached the knob 4 in the usual manner, and to the outer knob-spindle 5 is attached the outer knob 6, which knob may 45 be of any desired construction. The inner knob-spindle is not locked against operative rotation and is entirely disconnected from the outer spindle 5. To the outer spindle 5 is attached the notched head 7 by means of 50 screw-threads formed upon said outer spindle, and the inner spindle 3 is also attached to said head by means of screw-threads, but is so attached that it is free to rotate independent of the head in one direction, and 55 when so rotated by means of the inner knob 4 it actuates the bolt 8 in the ordinary man-

ner, which devices within themselves form no particular part of the present invention, and hence no description or illustration is necessary. Directly below the inner end of 60 the outer knob-spindle 5 is located the hollow bearing 9, which is formed integral with the lock-case 1 and in which hollow bearing is located the spindle 10, which spindle is free to be rotated by means of the knob 11. 65 Upon the hollow bearing 9 are loosely mounted the notched or counting disks 12, 13, and 14; but it will be understood that these parts may be duplicated, if desired, without departing from the nature of my invention. 70 Between the notched or counting disks 12, 13, and 14 are located the lock-disks 15, 16, and 17, which lock-disks are provided with the square-shouldered notches 18. Directly above the spindle 10 is located the gravity- 75 bar 19, which gravity-bar is provided with the T-head 20, the lower portion of the T-head being for the purpose of entering the notches 18 when said notches are brought into alinement, as hereinafter described. 80

The notched head 7 is designed to rotate with the outer knob-spindle 5; but it will be understood that said outer knob-spindle cannot be rotated when the T-head 20 is engaged with the notch 21 formed in the lower 85 portion of the head 7; but when said head is disengaged from the notch 21 the outer knob, together with its spindle, is free to rotate, which rotation operates the catch bar or bolt 8 in the usual manner. The T-head 20 is 90 held in elevation at all times, except when the notches 18 are brought into alinement and directly under the T-head 20, at which time said T-head is free to drop and release the head 7. The lock-disks 15, 16, and 17 95 are each provided with a series of apertures 22, which apertures are for the purpose of receiving the connecting-pins 23, which connecting-pins are secured to the notched or counting disks 12, 13, and 14, and when the 100 pins 23 are so connected the lock-disks and counting-disks move together—that is to say, one counting-disk and one lock-disk move in unison. It will be understood that by changing the pins 23 into different apertures in the different lock-disks a different combination is produced—as, for instance, the first or inner lock-disk may be connected to the aperture “3,” the next one aperture “4,” and the third one aperture “5,” which 105 would make the combination “3 4 5.” 110

It is well understood that all of the count

ing-disks should be brought into such a position that a given combination will open the lock, and in order to provide for this each counting-disk is provided with a tang 24, and 5 upon the extreme inner end of the spindle 10 is secured the disk or plate 25, which plate is provided with the pin 26, which pin is so located that it will come in contact with the tangs 24, and as the spindle 10 is rotated all of the 10 counting-disks, together with the locking-disks, will be brought to a predetermined position by reason of the tangs 24 coming in contact with the T-head 20. The movement of the spindle 10, which brings the tangs 24 15 against the T-head 20, places the lock in position to commence counting the predetermined combination to open the lock. For the purpose of elevating the T-head after it has dropped to release the head 7 the disk 25 20 is provided with the notch 27, which notch is provided with the inclined edge 28, which inclined edge permits the T-head to ride upon said inclined edge 28 and elevate said T-head; but by reason of the notches 18 in the locking-disks being formed with square shoulders or 25 edges said disks will be held against rotation in either direction. For the purpose of operating the various counting-disks the counting-bars 29 are provided, which counting-bars are each provided with the outward-extending knobs or lugs 30, and to said bars are attached the spring-tangs 31, which spring-tangs engage the teeth 32, formed upon the counting-disks. It will be understood that 35 when any given bar 29 is moved upward it will impart a rotary movement to the corresponding counting-disk by reason of the spring-tang 31. For the purpose of providing a means for limiting the upward movement of the counting-bars 29 the case 1 is provided with the slots 33, which slots are so formed that they limit the upward movement of the knobs 30. For the purpose of insuring the downward movement of the 40 counting-bars their bottom or lower ends are provided with the notches 34, and into which notches are seated the springs 35, as illustrated in the drawings. For the purpose of giving the proper tension to the lock-disks, together with the counting-disks, the spring 36 45 is provided, which spring is located substantially as shown in Fig. 2 and of the form shown in Fig. 8 and is designed to press against the peripheries of the lock-disks 15, 50 16, and 17. If desired, the spring 36 may be divided at its lower end and one division of the spring arranged to come in contact with one lock-disk. For the purpose of holding the counting-bars in proper position at their 55 top or upper ends a clip 37 is provided, which clip is connected to the casing 1 by the flange 38, and of course the spring 36 is located over the clip and at one side of the connecting-flange 38. It will be understood that the various lock-disks and counting-disks should

not move except when necessary, and in order that there may be no accidental movement of the various disks the division-plates 39 are provided, which are held against rotation by means of their notched ends and the 70 pin 40. For the purpose of causing the disk 25 to rotate with the spindle 10 and also for the purpose of economizing with reference to room said disk is provided with the slot 41, which slot receives the pin 42. For the purpose of holding all of the various disks in proper position upon the spindle the key 43 is provided and said key located through the spindle 10. For the purpose of stopping the head 7 at the proper point with reference to the T-head 20 the stop-pin 44 is provided, which stop-pin is secured to the casing 1 in any convenient manner, and for the purpose of causing the head 7 to be forced against the stop-pin 44 the spring 45 is provided and located substantially as shown in the drawings, and, as shown, it will be seen that said spring will press the head 7 against the stop-pin 44 when said head is free to move.

It will be understood the means for actuating the lock-bolt 8 are practically the same as the means in common use and that no change of said parts is necessary, thereby enabling my improved lock to be adapted to the common key-locks now in use.

Having fully described my invention, what I claim as new, and desire to secure by Letters Patent, is—

1. In a combination-lock a casing, separable knob-spindles and knobs connected thereto, one of the knob-spindles having connected thereto a notched head adapted to rotate with the spindle, a gravity-bar provided with a T-head, a spindle located in a plane below the knob-spindles, and in a hollow bearing, a series of lock-disks and counting-disks mounted upon the hollow bearing and concentric with the spindle located therein, and each lock-disk provided with a notch adapted to receive the lower end of the T-head, said counting-disks provided with tangs, and a disk rotatable with the spindle and provided with a pin adapted to engage the tangs of the counting-disks, counting-bars provided with knobs extended beyond the lock-case, means for actuating the counting-disks by the movement of the counting-bars, and means for connecting the counting-disks and lock-disks together at predetermined points, substantially as and for the purpose specified.

2. In a combination-lock of the class described, a casing, divided knob-spindles, a notched head operatively connected to one of the knob-spindles, a spindle located below the plane of the divided knob-spindle and in a hollow bearing, a series of counting and lock disks adapted to be separably connected one to the other, means for changing the point of connection between the lock-disks

- and counting-disks, means for actuating the counting-disks, a pivoted bar provided with a **T**-head, said lock-disks provided with notches adapted to receive the lower end of the **T**-head when said notches are brought into alignment, and a disk secured to the spindle located in a plane below the knob-spindles, said disk provided with a pin, said counting-disks provided with tangs adapted to be engaged by said pin, a friction-spring adapted to bear against the peripheries of the lock-disks, and dividing-plates located between the lock-plates, substantially as and for the purpose specified.
- 15 3. In a combination-lock of the class described, a knob-spindle provided with a notched head, a series of counting-disks and lock-disks located in a plane below the knob-spindle, a spindle located in a hollow bearing,
- a setting-disk secured to the spindle, a gravity-bar located intermediate the knob-spindle, and counting-disk spindle, and provided with a **T**-head, a pin secured to the setting-disk, said counting-disks provided with tangs adapted to be actuated by the rotations of the setting-disk, and the setting-disk provided with a notch having an inclined edge, means for connecting the counting-disks and lock-disks together, and means adapted to operate the counting and lock disks substantially as and for the purpose specified.

In testimony that I claim the above I have hereunto subscribed my name in the presence of two witnesses.

JOSIAH J. DEAL.
